UNITED STATES PATENT OFFICE

2,303,659

BAILER

Albert D. Purtle, Marietta, Ohio, and James R. Broadwater, Toll Gate, W. Va.

Application April 3, 1941, Serial No. 386,732

1 Claim. (Cl. 166—19)

The present invention aims to provide improved and novel means whereby liquid may be bailed out of an oil well or a gas well, especially a gas well, without loss of oil or gas, the bailing being done under pressure, the natural gas pressure in the well serving to discharge the bailed material, thereby saving the oil, the natural gas being salvaged, since the outlet for the bailed material is opened no longer than is necessary to permit the bailed material to be ejected, the outlet then being closed by an operator.

The present invention proposes improvements in the structure shown in our former Patent No. 2,130,026, granted on the 13th day of September, 1938.

Among the improvements disclosed hereinafter, may be mentioned making the top stuffing box longer than the lower box, to the end that more packing may be used about the sand line, the result being increased packing efficiency, with reduced friction. The casing head has been simplified and improved, the top part, with the fluid exit and stuffing box opening, being cast in one piece and including the valve seat.

The metal top valve and associated case, combined, includes a valve which, being composed of 70% lead and 30% tin, withstands the chemical properties of natural gas, the structure being capable of long continued use, without damage. The perforated, swivel rope socket prevents damage to wire sand lines, and places the pull nearer to the top of the bailer.

Improvements in the lower valve assembly cut down manufacturing costs and afford a structure which is more quickly assembled than the one shown in our aforesaid patent.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in elevation, a device constructed in accordance with the invention, parts being sectioned away;

Fig. 2 is a section on the line 2—2 of Fig. 1;

Fig. 3 shows in longitudinal section, a portion

of a device constructed in accordance with the invention;

Fig. 3a is a longitudinal sectional view, constituting a lower continuation of the mechanism shown in Fig. 3;

Fig. 4 is a cross section on the line 4—4 of Fig. 3;

Fig. 5 is a cross section on the line 5—5 of Fig. 3;

Fig. 6 is a cross section on the line 6—6 of Fig. 3a;

Fig. 7 is a cross section on the line 7—7 of Fig. 8;

Fig. 8 is a vertical sectional view showing certain parts through which the line or suspension member passes.

Figs. 7 and 8 relate to a modification.

The numeral 1 marks a well casing. The numeral 2 designates a casing head 2, including a body 3, internally threaded at its lower end to receive the upper end of the well casing 1. Circumferentially spaced openings 4 in the body 3 provide for the exit of natural gas. The opening 4 which is not in use is closed by a plug 5, and into the opening which is in use, a gas conduit member 6 is threaded.

The upper member of the casing head 2 is designated by the numeral 7, and includes a reduced tubular neck 8, into which a lateral outlet pipe 9 for liquid is threaded. A hand valve 10, under the control of an operator, is interposed in the outlet pipe 9. The upper member 7 of the casing head 2 is held on the body 3 by securing devices 11.

Referring to the modification shown in Figs. 7 and 8, parts hereinbefore and hereinafter described have been designated by numerals already used, with the suffix "a." In the smaller sizes of casing heads, the number of securing devices 11a may be reduced below the showing of Fig. 2.

In the upper end of the body 3 of the casing head 2 there is provided a machined recess 12, receiving a gasket 14. The upper member 7 of the casing head 2 is supplied with a depending annular rib 15, fitting closely in the recess 12, and exerting pressure on the gasket 14, under the impulse of the securing devices 11. In the upper member 7 and in its neck 8, an upwardly tapered seat or bore 16 is formed. The neck 8 of the upper member 7 of the casing head 2 is supplied at its upper end with a threaded opening 17.

The casing head structure 2 and associated parts constitute one of the structural changes effected in our patent hereinbefore mentioned.

Into the opening 17 in the neck 8 of the upper member 7 of the casing head 2, a nipple 18 is threaded. The nipple 18 has a neck 19, on which a lower stuffing box cap 20 is threaded. The stuffing box cap 20 advances a lower plunger 21, to compress a lower packing 22 in the neck 19. The stuffing box cap 20 is provided with an up-standing neck 23.

The numeral 24 designates an upper stuffing box cap, surmounted by an oil bowl 25. The upper stuffing box cap 24 is threaded on the neck 23 of the lower stuffing box cap 20, and advances a plunger 26 against packing 27 in the neck 23. The neck 23 is longer than the neck 19, and the packing 27 may be increased in height accordingly, increased packing efficiency being afforded, with reduced friction, upon a sand line 28 which passes downwardly through the packing box structures. Owing to the fact that the rib 15 of the upper casing head member 7 is received in the recess 12 of the body 3 of the casing head, the packing box structures are made unusually per-stable and correct alinement is secured, a perpendicular, right line travel in the sand line 28 being attained.

The packing box structure and associated parts constitutes another improvement over what is shown in our former Patent No. 2,130,026.

A bailer B is mounted for reciprocation in the well casing 1. The bailer B comprises a lower tubular section 29, which serves to prevent cavings from the bottom of the well hole from disturbing the action of a foot valve, to be described hereinafter. In order to facilitate the operation of the bailer, the lower tubular section 29 may be perforated, as indicated at 30. A reinforcing ring 31 is held in the lower end of the lower bailer section 29 by securing elements 32, the ring having an outstanding shoulder 33, against which the lower end of the bailer section 29 abuts. A coupling 34 is threaded into the upper end of the lower bailer section 29, or is held otherwise there-in, the coupling having an outstanding, annular rib 35, which engages the upper end of the bailer section 29. A valve seat 36 is threaded into the lower end of the coupling 34, and is provided with an annular flange 37, engaging the lower end of the coupling.

The numeral 38 designates a stem, mounted to reciprocate in the valve seat 36, the stem 38 carrying a guiding cage 39, shown in Figs. 3a and 6. The upper end of the stem 38 is turned off to form a reduced tip 40 and a transverse shoulder 41. An inverted, frusto-conical valve 42 cooperates with the upper end of the valve seat 36 and is mounted on the tip 40. The valve 42 is not threaded on the tip 40. The tip 40 is threaded to accommodate a nut 43, engaging the upper end of the valve 42 and binding it against the shoulder 41. The nut is held against rotation by a fastening device, such as a cotter pin 44, mounted in the tip 40.

The lower valve structure last above described is an improvement which characterizes the present application.

An intermediate bailer section 45 surrounds the upper part of the coupling 34 and abuts against the rib 35. Securing elements 46 hold the upper end of the coupling 34 in the intermediate bailer section 45. Within the upper end of the intermediate bailer section 45 is located the lower end of a coupling 47, having a transverse shoulder 48, engaging the upper end of the intermediate bailer section 45. The bore of the coupling 47

is enlarged in its upper portion, to form a downwardly inclined annular seat 49. The lower end of the coupling 47 is held in the upper end of the intermediate bailer section 45 by securing elements 50.

An upper bailer section 51 is threaded into the upper end of the coupling 47, and is provided with a transverse shoulder 52 which engages the upper end of the coupling 47, to space the lower end of the upper section 51 from the seat 49.

A downwardly tapered anchor 53 has its edge disposed in the space between the seat 49 and the lower end of the upper bailer section 51. Since the periphery of the anchor 53 is located below the lower end of the upper bailer section 51, the anchor is provided with any desired number of openings 54, to permit passage of fluid whilst the bailer is being emptied. The anchor 53 is provided with a reduced, depending neck 55, and in the neck and in the body portion of the anchor, a tapered socket 56 is formed. The lower end of the sand line 28 is babbitted in the socket 56.

The anchor 53 is free to rotate, either to the right or to the left, in the event that too much of the sand line 28 is lowered into the well after the bailer has reached the bottom of the well. Owing to the fact that the anchor 53 can rotate, the formation of kinks or loops in the sand line 28 will be avoided.

The rotatable anchor 53 and associated parts offers a further improvement.

The upper bailer section 51 is provided with an upstanding reduced portion 57, which is circumferentially grooved as indicated at 58, for cooperation with the slips of a fishing tool. The reduced portion 57 of the upper bailer section 51 is supplied with a smooth upstanding tip 59. Over the tip 59 fits an inverted cup-shaped abutment 60, packing 61 being disposed within the abutment. The abutment 60 has an upstanding neck 62.

A tubular stem 63 is mounted for reciprocation in the parts 57 and 59 of the upper bailer member 51. The lower end of the stem 63 is provided with a stop 64, adapted to cooperate with a shoulder 65 within the upper bailer member 51. A cup-shaped valve base 66 is threaded on the upper part of the tubular stem 63. The valve base 66 is circumferentially grooved, as shown at 67, to cooperate with the slips of a fishing tool. The valve base 66 is provided with a depending neck 68. A compression spring 69 abuts at its upper end against the valve base 66, and at its lower end against the cup-shaped member 60, which is carried by the tip 59 of the upper bailer section 51. The neck 62 on the abutment 60 and the neck 68 on the valve base 66 space the spring 69 from the tubular stem 63. In its side wall, the valve base 66 is supplied with circumferentially spaced openings 67.

The valve base 66 is held in a circular jig having a central core, and into the valve base is poured molten metal to form a valve 70, adapted to cooperate with the tapered seat 49 of the upper member 7 of the casing head. The molten metal crowns over the upper end of the base 66, the part of the metal that is within the base flowing outwardly, to form retaining plugs 71, in the openings of the valve base 66. The metal which is poured to make the valve 70 may comprise seventy percent lead and thirty percent tin. After the valve 70 has been poured, it is machined to shape. The valve 70 has an opening 72 in its top.

The valve base 66 and the valve 70 form an improvement over the patented structure mentioned hereinbefore.

The gross operation of the device herein disclosed is the same as that of the structure shown in Patent 2,130,026.

In practical operation, the bailer B is lowered in the well until the stem 38 opens the valve 42, and the bailer fills. The bailer is drawn upwardly, and the valve 42 closes, the liquid to be removed being trapped in the bailer. By means of the sand line 28, the bailer B is raised until the valve 70 comes into contact with the seat or bore 16, as in Fig. 3.

When the valve 70 engages the seat 16, the bailer B continues to move upwardly for a time, compressing the spring 69 and enhancing the tight joint between the valve 70 and the seat 16. The operator opens the valve 10 for an instant, and the gas pressure in the well unseats the valve 42 and forces the liquid in the bailer B up-

wardly through the tubular stem 63, and through the neck 8, the liquid passing through the outlet pipe 9. It is necessary to open the valve 10 for an instant only, and there is no loss of gas to speak of, in the emptying of the bailer. During the upward movement of the stem 63, the spring 69 acts as a cushion, limiting yieldably, the upward movement of the bailer.

What is claimed is:

10 In a well pump, a hollow first bailer member having a lower internal shoulder, a hollow second bailer member extended into the lower bailer member and forming an upper internal shoulder, an anchor mounted for free rotation between the shoulders and having an opening communicating with both bailer members, and means for reciprocating the bailer, said means being connected to the anchor.

ALBERT D. PURTLE.
JAMES R. BROADWATER.
